ABRADING DEVICE

Filed June 25, 1927

UNITED STATES PATENT OFFICE

WILLIAM STEVER, OF BERLIN, GERMANY, ASSIGNOR TO BEHR-MANNING CORPORATION, OF TROY, NEW YORK, A CORPORATION OF NEW YORK

ABRADING DEVICE

Application filed June 25, 1927. Serial No. 201,506.

The present invention relates to abrading devices and more particularly devices for attaching an abrading or sanding disc to a rotatable carrier head.

5 An object of the invention is to provide an attaching means for the abrading disc which is readily operable without the use of tools for clamping the disc to the rotating head.

10 A further object of the invention is to provide an attaching means which may be manufactured at an inconsiderable cost and readily applied to the usual type of head.

15 The above and other objects of the invention of a generally similar nature will become clearer as the description proceeds in connection with a preferred embodiment shown in the accompanying drawing, wherein

20 Figure 1 is an edge view of a rotatable head showing the disc applied thereto.

25 Figure 2 is a sectional view taken through the head showing the attaching devices in operative position.

Figure 3 is a view similar to Fig. 2 taken at a slightly different angle showing the position of the movable parts of the attaching device before the disc is secured in position.

Figure 4 is a face view of the hub portion of a disc.

Figure 5 is a perspective showing the movable part of the attaching device.

Figure 6 is a sectional view on substantially the line 6—6 of Fig. 4 showing the relative positions of the disc and clamping element.

35 Figure 7 is a face view of the disc.

Referring to the drawings, 10 indicates the drive shaft of any suitable mechanism having a housing 10' (Fig. 1), the shaft having a threaded end 10'' reduced to fit within the

40 hollow hub portion 11 of a head having a peripheral portion 12 secured to a backing plate 13 by means of rivets 14. The marginal portion 12 of the head is, in the present instance, of relatively flexible material, such as felt, and the backing 13 is of relatively stiffer material, which does not extend to the edge of the peripheral portion so as to permit the latter to yield or flex adjacent its edge. Heads of this type are old and well known in the art, and are shown, for example, in the patent to

Stratford, 1,558,714, granted December 15, 1924. It will be understood that the present invention is not limited to use with this particular type of yielding head, and is simply shown as associated therewith for purposes of illustration.

The backing 13 of the head is formed of a plurality of layers or plies 13', 13'', all of which are secured to the projecting flange 11' of the hub 11 by means of screws 15, which pass through openings therein into a centrally disposed plate 16 having a bevelled inner periphery 17, which assists in clamping the flexible pad or head portion 12 to the backing 13 adjacent the center of the head. The plate 16 has a central aperture or a hub opening 18 within which is centrally disposed the projecting tubular portion 19 of the hub 11, the latter having thereon a circumferential cam groove 20, which receives a follower pin 21 fixedly positioned on a collar 22 having a closed end 23.

The collar is provided with a pair of wings 24, 25, each wing having an upwardly deflected terminal portion 26, the edges 27, 28 of which are disposed on opposite sides of the head axis and of the hub 22.

As will be observed, the wing edges 27, 28 and their adjacent raised portions 26 extend outwardly a sufficient distance to overlie the outwardly and upwardly inclined top surface 29 of the plate 16 (Fig. 3) and the wings are inclined so that upon rotation of the collar 22, they will be moved downwardly toward the face 29 to depress the central portions of a sanding disc which they overlie, as illustrated in Fig. 6.

The attachment device is maintained to be employed with a sanding disc 9 as is shown in Fig. 7 having a centrally disposed opening 30 with radially disposed slits 31 leading therefrom and disposed on opposite sides of openings 30. When the disc is to be applied to the head, edges of the slits 31 on opposite sides of a line extending through both slits 31 are depressed slightly and then the disc is placed upon the head so that the closed end 23 of the collar will project through the opening 30, the collar thus serving as a centering hub for the disc. Pressure upon the

opposite edges of the slits, such as the edge 32 and the edge 33 will lower them sufficiently to bring them to a plane below the raised ends 27, 28 of the wings 24. The disc may then be 5 rotated relative to the wings and centering collar 22 to carry the edges 32, 33 respectively beneath the raised wing edges 27, 28. If necessary, the hub collar 22 and wings may be held against rotation with the disc by inserting a suitable tool such as a spanner wrench within the sockets 35 in the closed end 23 of the hub. When the disc has been rotated sufficiently so that the raised terminal portions 26 of the wings 24, 25 overlie the 10 edges 32, 33 of the disc slits the central hub portion will then turn with the disc (providing it is released if it has been held against rotation as described) and the follower pin 21 working in the cam slot 20 will draw the 15 hub collar inwardly to depress those edges 32, 33 of the disc slits underlying the wing portions 26. This depressing engagement will be continued since the clamping device is so arranged upon the head that the latter 20 will rotate in a counter-clockwise direction, as illustrated by the arrow 36 in Fig. 4, and pressure upon the sanding disc due to this 25 rotation will tend to force the attaching device in the opposite or clockwise direction.

30 When it is desired to renew the sanding disc it is simply necessary to rotate the same in the direction of the arrow 36, or if desired, the collar 22 may first be rotated by engaging a tool with the sockets 35 to raise 35 the wings toward the plane of the supporting disc supporting surface of the head marginal portion.

Obviously, the construction may be modified considerably without departing from the 40 invention, which is defined in the following claims:

I claim:

1. A device of the class described comprising a rotatable head having a substantially flat surface adapted to support a sanding disc, and a centrally disposed attaching device comprising a projecting centering hub portion and wings having free edges disposed on substantially opposite sides of said 45 hub and arranged substantially radially with respect thereto, said wings being arranged on substantially opposite sides of said hub, and being movable toward and from the plane of said disc supporting surface, whereby to be lowered relative to said supporting surface upon association of the wings with a disc, said hub being adapted to fit within a central opening of a sanding disc and the edges of said wings being adapted to project into openings in the disc arranged on opposite sides of said central opening.

2. A device of the class described comprising a rotatable head having a substantially

vice comprising a projecting centering hub portion and wings having free edges disposed on substantially opposite sides of said hub and arranged substantially radially with respect thereto, said wings being arranged on substantially opposite sides of said hub, and being movable toward and from the plane of said disc supporting surface upon rotation of said hub, whereby to be lowered relative to said supporting surface upon association of the wings with a disc, said hub being adapted to fit within a central opening of a sanding disc and the edges of said wings being adapted to project into openings in the disc arranged on opposite sides of said central opening, and means for raising and lowering said hub and wings when the hub is rotated.

3. A device of the class described comprising a rotatable head having a substantially flat surface adapted to support a sanding disc, and a centrally disposed attaching device comprising a projecting centering hub portion and wings having free edges disposed on substantially opposite sides of said hub and arranged substantially radially with respect thereto, said wings being arranged on substantially opposite sides of said hub, and being movable toward and from the plane of said disc supporting surface upon rotation of said hub, whereby to be lowered relative to said supporting surface upon association of the wings with a disc, said hub being adapted to fit within a central opening of a sanding disc and the edges of said wings being adapted to project into openings in the disc arranged on opposite sides of said central opening, and means for raising and lowering said hub and wings when the hub is rotated.

4. A device of the class described comprising a rotatable head having a substantially flat surface adapted to support a sanding disc, and a centrally disposed attaching device comprising a projecting centering hub portion and wings having free edges disposed on substantially opposite sides of said hub and arranged substantially radially with respect thereto, said wings being arranged on substantially opposite sides of said hub, and being movable toward and from the plane of said disc supporting surface upon rotation of said hub, whereby to be lowered relative to said supporting surface upon association of the wings with a disc, said hub being adapted to fit within a central opening of a sanding disc and the edges of said wings being adapted to project into openings in the disc arranged on opposite sides of said central opening, the wings being engageable and rotatable by rotation of a sanding disc when the latter receives said wings, and means for raising and lowering said wings and hub upon said

ing a rotatable head having a substantially flat surface adapted to support a sanding disc, and a centrally disposed attaching device comprising an outwardly projecting centering hub portion and wings having free edges disposed on substantially opposite sides of said hub and arranged substantially radially with respect thereto, said wings being arranged on substantially opposite sides of said hub, and being movable toward and from the plane of said disc supporting surface upon rotation of said hub, whereby to be lowered relative to said supporting surface upon association of the wings with a disc, said hub being adapted to fit within a central opening of a sanding disc and the edges of said wings being adapted to project into openings in the disc arranged on opposite sides of said central opening, and means for raising and lowering said wings upon said head as the wings are rotated, said wings being rotatable by a sanding disc when the latter is associated with the wings, said raising and lowering means comprising follower means associated respectively with said hub and wings, and a cam slot on said head.

In testimony whereof I have hereunto set my hand.

WILLIAM STEVER.
